UNITED STATES PATENT OFFICE.

SAMUEL J. LAVEZZI, OF CHICAGO, ILLINOIS, ASSIGNOR TO HERZ BED COMPANY, OF CHICAGO, ILLINOIS, A CORPORATION OF ILLINOIS.

DAY BED AND THE LIKE.

Application filed May 21, 1921. Serial No. 471,448.

My invention relates to what are known as day beds and the object thereof is to provide a simple and efficient construction of bed or couch of this character. The various features of advantage and utility in my construction will be apparent from the description hereinafter given.

In the drawings Fig. 1 is a plan view of a portion of the bed or couch extended with the mattress removed; Fig. 2 an end elevation of the structure or frame sections of the bed with the mattress shown in dotted lines; Fig. 3 a view similar to Fig. 2 but showing the movable frame section in closed position and superimposed upon the stationary section; Fig. 4 a plan view of a portion of the structure shown in Fig. 3; Fig. 5 a section on the line 5—5 of Fig. 2; Fig. 6 a section taken through the parts shown in Fig. 5 to show a guide roller in cross-section; Fig. 7 an end elevation of a bed showing the application of bed ends thereto; Fig. 8 a side elevation partly in section of the structure of Fig. 7; Fig. 9 a plan view of a portion of the bed shown in Fig. 7 and Figs. 10 and 11 details showing the means of connection between a bed post and the stationary frame of the bed.

Referring to the embodiment of my invention as shown in Figs. 1 to 6, the bed comprises two sections one a stationary frame section and the other a movable frame section, which sections are pivotally connected together by pairs of parallel links, having a parallel roller motion and cooperation with suitable tracks for guiding the movements of the movable section.

The stationary section comprises a frame preferably made of angle iron and composed of vertical posts 1 connected together at the ends by the upper end bars 2 and lower end bars 3 and connected at opposite sides by the upper side bars 4 and lower side bars 5. For strengthening the frame structure suitable corner braces 6 are provided. Each end of the stationary section is provided with a half ring 7 having an upward projection 8 whereby it is fastened to the top bar 2 as by means of rivets 9. The lower ends of this member or ring 7 are provided with flanges 10 as shown in Fig. 5 the same being secured to the lower bar 3 in suitable manner as by the rivets 11. This member or ring 7 is provided with an arcuate slot 12.

The movable section comprises top bars 13 which are connected towards their inner ends by means of transverse bar 14 and at their outer ends by the side bar 15. Both frames are provided with spring fabric 60 either of the link type as shown at 16 or of the coiled wire fabric type as may be desired.

The movable section is pivoted upon the stationary section by the pairs of parallel links 17, 18 it being understood that each end of the bed is provided with a pair of these links, one pair of such links being shown in the drawings. Referring to the links at one end of the bed and bearing in mind that the construction is the same at the other end the link 17 is pivotally connected at its upper end to the end bar 13 by the bolt or rivet 19, and at its lower end to the end bar 3 by the bolt or rivet 20. The other link 18 is pivotally connected to the end bar 13 by the bolt or rivet 21 and to the bar 3 by the bolt or rivet 22. These two links are connected together by means of the link 23 which is pivotally connected 80 thereto at points intermediate their length. This cross link 23 is pivotally connected to the link 18 by the bolt or rivet 24 and to the link 17 by the pin or rivet 25. This pin extends through the links 23 and 17 and 85 through the slot 12, and also passes into and is secured to the flange end 26 of the cross member or bar 27 which extends to the other end of the stationary frame. In order to reduce the friction a small roller 28 is mounted on the pin 25 and is adapted to travel in the slot 12, such roller being made in sections as shown in Fig. 6 so that it may be properly assembled in place. The connecting bar 27 is provided at each end with the 95 flanged end 26 which is shaped as shown in Fig. 5 and secured at its extreme end to the link 17 by the rivets 29.

Describing the operation and beginning with the parts as shown in Fig. 3, the movable section is drawn outwardly, that is to the right as shown in Fig. 3 for which purpose a handle 30 may be employed. In this movement the bed and the links 17, 18 move to the position shown in Fig. 2, the pins 25 100 and their rollers traversing the length of the slot 12 and finally coming to rest at the right hand end of such slots at which time the vertical post 31 of the movable section rests upon the floor. The mattress which is in- 110

dicated in dotted lines at 32 which has heretofore been in folded condition as shown in Fig. 3 is now opened out to the position shown in Fig. 2.

5 When the bed is in the opened position shown in Fig. 2 the movable section is supported by the posts 31 and by the rollers 28 resting in one end of the slots. When the bed is in closed position as shown in Fig. 3
10 the movable section is supported by means of these rollers 28 resting in the other ends of the slots and also supported by the angle irons 33 (which are secured to the posts 31) resting upon the rests or angle irons 34 upon
15 the vertical posts 1 as shown in Figs. 2 and 3.

In Figs. 7 to 11 I have shown the application to this construction of bed of bed ends such as indicated at 35, it being understood that a similar bed end is provided at
20 the other end of the bed or couch. In this application of the bed end to the bed I have provided suitable connecting and supporting means. The bed ends are provided with posts 36 which are hollow at least at their
25 lower ends to provide openings 37 for the connecting and supporting device now to be described. The posts 1 are provided with angle irons 38 provided with closed end portion 39 having a hole or opening 40. Each
30 of the supporting devices which are shown alone in Fig. 11 consists of a vertical pin 41 inserted in the opening 37 of a bed post and a laterally and upwardly extending member or bar 42 provided with an upwardly
35 extending small pin 43 which is received by the hole 40. This device thus not only connects the lower ends of the bed posts to the bed but also supports the latter a distance above the floor as shown in Fig. 8. The bed
40 and each bed end is connected by additional means such as the link 44 pivoted by the bolt 45 to the cross bar or tube 46 of the bed end. As shown in Figs. 8 and 9 the inner end of the link 44 is made hook shape so as
45 to hook over the pin 47 in the lower bar 3 of the bed. Another link 48 is pivoted to the bed end at 49 and likewise provided with a hooked inner end so as to engage over the pin 50 on the bed.

50 Thus in a very simple and economical manner bed ends may be provided for the bed or couch in order to suit the wishes of customers. A customer may desire to purchase merely the bed while another customer
55 may prefer to purchase a bed plus the bed ends. For these two transactions the same type of bed is employed and the bed ends are so made as to be readily applied to or detached from the bed structure.

60 I claim:

1. A device of the class described comprising a stationary frame section and a movable frame section pivoted thereon, and bed ends having corner posts, and inwardly
65 and upwardly projecting members on the

lower ends of said posts upon which the stationary frame section is detachably supported.

2. A device of the class described comprising a stationary frame section and a movable frame section pivoted thereon, and bed ends having corner posts, and inwardly and upwardly projecting members at the lower ends of said posts upon which the stationary frame section is supported, said members being detachably connected with said frame and posts respectively.

3. A device of the class described comprising a stationary frame section and a movable frame section pivoted thereon, and bed ends having corner posts hollow at their lower ends, the stationary frame section being provided at its corners with openings, and supporting and connecting members, each consisting of a pin portion entering the lower end of a post and a laterally and upwardly projecting portion provided with a pin entering one of the openings in the said stationary frame section.

4. In a device of the class described, the combination of a stationary bed section having legs adapted to rest on the floor, detachable bed ends having legs, extending feet on the legs of said bed ends supported on the floor and also adapted to engage the lower ends of the legs of the stationary bed section, so that the latter is supported at substantially the same height as when the bed ends are not attached, and detachable means for connecting said bed ends in spaced relation to said stationary bed section at points above the lower ends of the legs of the stationary bed section.

5. In a device of the class described, the combination of a stationary bed section, a movable bed section, links connecting the bed sections at their ends to permit the movable section to be swung over the stationary section, detachable bed ends having legs, feet extending from the lower ends of the legs of the bed ends and adapted to engage the lower ends of the legs of the stationary bed section to support the latter at substantially the same height as the same is supported on the floor when the bed ends are not attached, and detachable means for connecting said bed ends to said stationary bed section at points above the lower ends of its legs and in spaced relation thereto to accommodate the swinging links.

6. In a device of the class described, the combination of a stationary bed section having legs adapted to rest on the floor, detachable bed ends having legs, extending feet adapted to support the bed ends on the floor and also adapted to engage the lower ends of the legs of the stationary bed section so that the latter is supported at substantially the same height on the floor as when the bed ends are not attached, vertical pro-

jections on said feet engaging aligning apertures in the lower ends of the legs of the stationary bed section, and detachable means for connecting the bed ends to the stationary bed section at points above the lower ends of its legs.

7. In a device of the class described, the combination of a stationary bed section having legs adapted to rest on the floor and having horizontal members at their lower ends provided with apertures, detachable bed ends having legs, extending feet on the bed ends supported on the floor and also adapted to engage the lower ends of the legs of the stationary bed section to support the latter at substantially the same height on the floor

as when the bed ends are not attached, detachable means for connecting the bed ends to said stationary bed section at points above the lower ends of the legs, a movable bed section, means attached to the ends of the stationary bed section for permitting swinging movement of the movable section, said means being positioned between the ends of the stationary bed section and the detachable bed ends, the feet end detachable means being extended so that the bed ends are in spaced relation with respect to the ends of the stationary bed sections to accommodate said means.

SAMUEL J. LAVEZZI.
